UNITED STATES PATENT OFFICE.

KATHERINE E. BURNS, OF NEW YORK, N. Y., ASSIGNOR TO FRANKLIN SIMON & COMPANY, INC., OF NEW YORK, N. Y., A CORPORATION OF NEW YORK.

DESIGN FOR A DRESS.

Application filed August 31, 1928. Serial No. 28,013. Term of patent 3½ years.

To all whom it may concern:

Be it known that I, KATHERINE E. BURNS, a citizen of the United States, and a resident of the city of New York, borough of Manhattan, in the county of New York and State of New York, have invented the new, original, and ornamental Design for Dresses, of which the following is a specification.

Reference is to be had to the accompanying drawings forming a part of this specification.

Figure 1 is a view in front elevation of a dress showing my new design;

Figure 2 is a view in rear elevation of the same.

I regard as the dominant feature of my design the distinct lines tapering from a point below the arm pits to the waist, in connection with the heart-shaped neck opening, which gives a heart-shaped design to the upper front portion of the dress.

I claim:

The ornamental design for a dress as shown and described.

Signed at New York, in the county of New York and State of New York, this 27th day of August, A. D. 1928.

KATHERINE E. BURNS.
